UNITED STATES PATENT OFFICE.

ELBERT D. WILLIAMS, OF COLORADO, TEXAS.

FISHING-REEL.

SPECIFICATION forming part of Letters Patent No. 580,025, dated April 6, 1897.

Application filed December 3, 1895. Serial No. 570,899. (No model.)

To all whom it may concern:

Be it known that I, ELBERT D. WILLIAMS, a citizen of the United States, residing at Colorado, in the county of Mitchell and State of 5 Texas, have invented certain new and useful Improvements in Fishing-Reels, of which the following is a specification.

My invention relates to fishing-reels; and the object thereof is to improve the operation 10 of the same, as will be hereinafter described, and particularly specified in the claims.

The invention is illustrated in the accompanying drawings, in which—

Figure 1 is a side elevation of the reel connected to a section of a fishing-rod with the end cap and crank removed. Fig. 2 is an end elevation of the same, the rod not being shown. Fig. 3 is a side elevation showing the parts in operative position. Figs. 4 and 5 are side and 20 end elevations, respectively, of a modification. Fig. 6 is a detail view.

Similar letters refer to similar parts throughout the several views.

A represents a reciprocating lever hung to 25 a part of the frame. The end cap, which is shown only by dotted lines, I construe to be a part of the frame, B being an arm connection of lever.

C is a connection between arm B and reciprocating rack-bar D, whose teeth engage the ratchet-teeth of the wheel E when the mechanism is in use.

F shows an auxiliary gear mounted on an auxiliary shaft and engaging with pinion G, which is attached to shaft S.

H is an arm hung on pivot K. This arm is weighted and has a light end or projection which, through the gravity of the weighted part of the arm, presses against the rack-bar, 40 and thereby holds it in engagement with the ratchet-wheel teeth when the rack-bar is below the ratchet-wheel, and its gravity tends to draw it out of engagement with the ratchet-wheel teeth.

L is a plate forming, with the guides J, a guideway for the rack-bar D and a seat for the pivoted weighted arm H. M shows a stop to limit the movement of the weighted arm H.

S is a rotative shaft mounted in the casing 50 or frame.

R represents handhold of fishpole.

T is a sliding pawl journaled at Z to fit loosely over the pin Q, which slides it. This

pin is a connection of a sliding knob, (shown on outside of cap by dotted lines O.) 55

U shows pawl-spring secured to outside plate, and Y shows pins secured to plate and turned over at the outer end to form guide for pawl. These pins also form a stop for the pawl when working in connection with pin Q. 60 The dotted lines at each end of pawl show its position when not in use.

The operation of my mechanism is as follows: The lever A is pressed toward the handhold of fishpole, drawing its connections B 65 and C with it and drawing the toothed rack-bar D into engagement with the teeth of the ratchet-wheel E, thereby revolving it and its connecting rotary mechanism. When the lever A is released, the retracting-spring P, 70 pushing on lever A, will, through its connections, push the rack-bar D back over the slanting teeth of ratchet-wheel, the teeth of rack-bar and ratchet-wheel being out of engagement, the pawl T preventing any loss of motion gained. 75

The operation is a reciprocating motion and may be repeated rapidly or at intervals, as desired. Toward the end of the retracting stroke the outer end of the rack-bar stops 80 against the outside cap or a stop may be used, and the end at connection is pushed out of its course and back against the outside guideway J, where it is entirely clear of the ratchet-wheel, and it remains in this position until 85 the lever A is pressed again, when its own gravity will bring its teeth in contact with the ratchet-wheel teeth if it is above the ratchet-wheel, and if it is below the ratchet-wheel the light end or projection of the pivoted arm H through its gravity in its weighted part will then raise the rack-bar into engagement with the teeth of the ratchet-wheel. 90

It will be seen that this mechanism in no way interferes with the crank-handle and rotary mechanism in common use and they can both be used on the same reel to give a variety of work and convenience or my mechanism can be used alone, if desired. 95

It is obvious that this mechanism can be 100 used on a single-acting reel by placing the ratchet-wheel on the rotative shaft S, as shown in Fig. 4, instead of on an auxiliary wheel.

It is also obvious that a reel with this mechanism can be attached to a fishpole in various 105 positions, for instance, either above or below

the handhold or with one of its sides toward the pole, by simply shaping the lever so that it is within easy reach of the handhold, and its use in a fishing-reel of any character in 5 no way affects my invention.

Some of the advantages of my invention are as follows: It is simple and inexpensive in its construction and its movement may be very rapid. It in no way interferes with the rotary mechanism in bait or fly casting. A cast 10 can be stopped at any distance or a fish can be instantly stopped from unreeling too much line when the pawl is not in use by pressing the lever-handle toward handhold of pole and 15 holding it there. It can be operated by a thumb or finger of the hand that holds the pole, leaving the other hand free to use the landing-net.

Having fully described my invention, what 20 I claim, and desire to secure by Letters Patent, is—

1. In combination with a reel adapted to be detachably secured to a fishing-rod, the spindle, the toothed wheel, the sliding rack, the 25 spring-pressed lever, the lateral arm extending therefrom, the link C connecting the same, with said rack to operate it and to press the same into and out of contact with said wheel.

2. In combination, the reel-spindle and toothed wheel, the rack with means for re- 30 ciprocating the same, the weighted lever arranged adjacent to said rack for throwing the rack into engagement with the toothed wheel, substantially as described.

3. In combination, the spindle, the toothed 35 wheel, the rack, the lever and link C connecting said lever and rack, and the guides for controlling the longitudinal movement of said rack, said guides being in direct contact therewith, substantially as described. 40

4. In combination, the reel with its spindle, the toothed wheel on the spindle, the frame carrying the reel with its spindle, said frame being adapted for attachment to a fishing-rod, a loose rack, a lever connected thereto for 45 operating the same and a guide on one of the lateral faces of the reel-frame engaging the said loose rack, substantially as described.

In testimony whereof I have hereunto set my hand on this the 29th day of November, 50 1895.

ELBERT D. WILLIAMS.

In presence of—

E. T. COLLINS,
B. F. WILSON.
